DRILLING AND DEFLECTING TOOL

Daniel B. Hering, Lakewood, Calif., assignor to
Driltrol, Long Beach, Calif.

Application September 24, 1956, Serial No. 611,570

19 Claims. (Cl. 255—1.6)

This invention relates to a new and improved drilling and deflecting tool. This application is a continuation-in-part of my co-pending patent applications Serial No. 486,329, filed February 7, 1955, now abandoned, and Serial No. 514,646, filed June 10, 1955, now abandoned. For various mechanical or geological reasons it is sometimes desirable that the course of an existing bore hole for an oil or gas well or similar hole be diverted or deflected from its existing direction, so that a new section of the hole assumes an angle with respect to the pre-existing section. The present invention relates to a tool which may be used to accomplish this diversion or deflection.

One distinction between the present invention and other tools heretofore used for deflecting bore holes is emphasized by consideration that in previously used tools it is necessary first to drill a hole with a conventional drilling tool to the desired depth, then raise that tool to the surface, insert a tool which accomplishes deflection of the hole, perform the deflecting operation, then remove the deflecting tool from the hole, and then reinsert the conventional drilling tool and continue drilling in the deflected direction. The tool which is the subject of the present invention may be used to drill to the desired depth, then deflect the hole, and continue drilling in the deflected direction, all without removing the tool or any part of the tool, from the hole. This is of considerable advantage in that removal and reinsertion of a drilling tool and the drill pipe string is extremely expensive, both from the standpoint of wear and tear on the machinery, fuel consumption and rig and crew times. Accordingly, the present invention eliminates the time and expense involved in conventional operations.

Another feature of the invention is the fact that means is provided to orient the tool to deflect in any desired direction. Furthermore, the tool may be used to make several successive deflections without removing the tool from the hole at different depths. The succeeding deflections may be made in a desired direction different from the preceding deflection.

The present invention comprises a tool which may be lowered into the bore hole and employed to drill the hole in a manner quite similar to conventional drilling practices until such time as deflection of the hole is desired. Thereupon the present tool may be used to accomplish deflection of a new section of the bore hole at an angle with respect to the pre-existing section. Thereafter the new section of the hole may continue to be drilled by means of the present tool in a manner substantially similar to conventional drilling practices. One of the features and advantages of the present invention is the fact that the tool may be used alternately for conventional drilling and deflection drilling without removing the tool from the hole for a number of alternations until the drilling of the hole is completed.

Another feature of the invention is the fact that it employs a guide used to deflect the direction of the hole, which guide may be retracted to an inoperative position

2

whereupon the tool may be used for drilling in a conventional manner and the guide may be projected and retracted as desired, without the necessity of returning the tool to the surface.

5 One of the principal features and advantages of the invention is the provision of latch means operable to latch the guide in retracted position and further latch means to latch the guide in projected position, both latch means being preferably operable both for latching and unlatching without raising the tool to the surface.

10 Another feature of the invention is the fact that the means which holds the guide in projected position comprises a latch which may be repeatedly latched and unlatched, thereby differing from other tools of the same general type which employ shear pins and similar instrumentalities which may be accidentally broken and hence prevent proper orientation of the tool. The tool which is the subject of the present invention may, accordingly, be positively oriented in proper direction and the guide locked against rotation while deflecting.

15 Another principal feature of the present invention is the elimination of a whipstock, which is the common means of deflecting bore holes at the present time. Further, the present invention eliminates the necessity of drilling the deflected hole, termed the "rathole," at a reduced diameter as compared with the diameter of the pre-existing hole, which is a feature of whipstock drilling at the present time.

20 The present invention materially reduces the amount of time required to deflect a bore hole, as compared with prior tools intended to accomplish the same purpose. The reduction in the time required is accomplished in large part by eliminating the necessity of returning the working tool to the surface by withdrawing the drill pipe and then lowering a new tool and drill pipe into the hole. The elimination of the replacement of the working tool results in a considerable decrease in drilling costs, particularly when the drilling is being conducted far below the surface.

25 Other objects of the present invention will become apparent upon reading the following specification and referring to the accompanying drawings in which similar characters of reference represent corresponding parts in each of the several views.

30 In the drawings:

Fig. 1 is a side elevation partly broken away in section showing one form of the tool at the completion of drilling of the pre-existing hole, with the guide retracted;

Fig. 2 is a view similar to Fig. 1 showing the drill retracted and the guide extended to commence drilling of the deflected hole;

Fig. 3 is a view similar to Fig. 1 showing partial completion of deflection of the bore hole;

Fig. 4 is a transverse sectional view taken substantially along line 4—4 of Fig. 2;

Fig. 4A is a transverse sectional view taken substantially along line 4A—4A of Fig. 1;

Fig. 4B is an enlarged fragmentary longitudinal sectional view of the upper latch;

Fig. 5 is an enlarged fragmentary sectional view of a modified upper latch;

Fig. 6 is an enlarged fragmentary longitudinal sectional view of a modified lower latch;

Fig. 7, 7A, 8 and 8A are enlarged fragmentary longitudinal sectional views of still other modified latches;

Fig. 9 is a fragmentary longitudinal sectional view of a spring-biased knuckle joint used in still a further modification of the invention;

Fig. 10 and 12 are longitudinal sectional views of additional modifications of the invention;

Fig. 11 is a transverse sectional view taken substantially along line 11—11 of Fig. 19;

Fig. 13 is a side elevation, partly broken away in section, of a modified tool shown at completion of drilling of the pre-existing hole, with the guide retracted;

Fig. 14 is a longitudinal vertical sectional view showing the drill retracted and guide extended to commence drilling of the deflected hole;

Fig. 15 is a view similar to Fig. 14 showing partial completion of deflection of the bore hole;

Fig. 16 is a view similar to Fig. 14 showing completion of deflection with the guide retracted;

Fig. 17 is a transverse sectional view taken substantially along line 17—17 of Fig. 14;

Fig. 18 is a longitudinal vertical sectional view of a modified tool;

Fig. 19 is a fragmentary vertical sectional view of the upper end of the tool showing a latch in latched position;

Fig. 20 is a view similar to Fig. 19 showing the latch being unlatched.

As shown in Figs. 1—4B of the accompanying drawings, a pre-existing bore hole 21 extends vertically and a new bore hole 22 is to be drilled at an angle to the pre-existing hole. It will be understood that it is not necessary that the pre-existing hole 21 be vertical and, further, that the angle which the new hole 22 assumes to pre-existing hole 21 is subject to considerable variation. In order to accomplish deflection of the new hole a tool is employed, as hereinafter described in greater detail, at the lower end of a string of drill pipe 23. If desired, the tool may be used to drill original hole 21 as well as deflected hole 22. The tool may be alternately used to drill a section of the hole along a pre-existing direction and then deflect along a new section, without the necessity of withdrawing the tool to the surface.

The tool comprises a barrel 26 having at its lower end an apertured drilling bit 27 herein termed the "core bit" by reason of its similarity to bits employed to sample formations by coring and a guide 28 projectable and retractable through the aperture 29 in bit 27. The barrel 26 has an extended cylinder portion 31 above core bit 27. Above cylinder portion 31 the barrel is formed with a reduced diameter section 32, there being a top shoulder 33 at the juncture of the cylinder portion and the reduced diameter portion which limits upward movement of guide 28 inside barrel 26. Above shoulder 33 is an upper latch cavity 34 hereinafter described in greater detail. Adjacent the lower end of cylinder portion 31 is a deflected cylindrical section 36 of substantially the same diameter as cylinder portion 31, said deflected cylindrical portion veering outwardly relative to the central axis of the barrel. Below deflected cylindrical section 36 is core bit 27, the construction of which is subject to considerable variation, as will be understood by those skilled in the drilling arts.

Bit 27 is so constructed as to drill a hole 21 of substantially greater diameter than the outside diameter of barrel 26. As has been heretofore set forth, bit 27 is formed with central aperture 29. Above aperture 29 intermediate said aperture and the lower end of deflected cylindrical section 36, the internal diameter is reduced to a bottom shoulder 37. A lower latch cavity 38, hereinafter described in greater detail, is formed near shoulder 37.

Guide 28 comprises an elongated stem 41 having a guide bit 42 at its lower end. A piston 43 is formed on the upper end of the guide stem, said piston having an outside diameter such as to slide longitudinally in both cylinder portion 31 and deflected cylindrical section 36. Above piston 43 is a restricted diameter head 44 formed with a recess 46 in which a latch 47 is mounted by means of pivot pin 48, spring 49 biasing latch 47 outwardly. Latch 47 and upper latch cavity 34 are so related that when in latched position the working end 51

of latch 47 is held retracted, with the point of guide bit 42 drawn within or near to aperture 29 of core bit 27. However, the point of guide bit 42 is sufficiently close to the lower edge of core bit 27 that when the tool is turned in a bore hole, guide 28 tends to remain stationary and this tendency is used automatically to unlatch the guide when the tool is turned in the reverse of the direction for normal drilling. Working end 51 of latch 47 is formed with a vertical outwardly extending surface 52 on one surface and a rounded, beveled shoulder 53. The lower edge 54 of the working end is substantially horizontal. Bottom wall 56 of upper latch cavity 34 is slightly helical and at its uppermost point terminates in vertical wall 57 against which vertical surface 52 engages so that guide 28 and barrel 26 rotate in one direction together. Outer wall 58 of cavity 34 and also the upper wall 59 thereof are eccentric, having their maximum outward projection against vertical wall 57 and diminishing as the helical bottom wall 56 lowers. It will thus be seen that when the tool is turned in a reverse direction, guide 28 remains stationary, latch 47 is retracted until guide 28 is unlatched, thereby permitting the guide to project through aperture 29 in core bit 27 when the tool is raised from the bottom of the bore hole.

Below piston 43 a seat 61 is formed on stem 41, which seat engages the corresponding aperture 29 in core bit 27. A recess is formed in seat 61 and bottom latch 77 which functions to secure guide 28 in projected position, is pivotally mounted in said recess by means of pivot pin 78, latch 77 being biased outwardly by means of spring (not shown) in said recess. The upper edge of latch is slanted and the corresponding upper wall 103 of latch cavity 38 is likewise slanted. Hence when extreme downward force is applied to barrel 26, latch 77 is retracted, permitting barrel 26 to be lowered while guide 28 remains stationary.

In use, as shown in Fig. 1, centrally apertured core bit 27 is employed to drill pre-existing bore hole 21 in substantially conventional manner with guide 28 retracted within the barrel and latched in position by upper latch 47 seating in latch cavity 34. Normal turning of drill pipe 23 causes surface 52 and wall 57 to engage and hence guide 28 turns with barrel 26. Assuming that it is desired to drill a deflected hole 22 after pre-existing hole 21 has reached the depth indicated in Fig. 1, the operator turns drill stem 23 in a direction counter to normal drilling direction, which causes upper latch 47 to unseat from latch cavity 34 and then raises the tool from the bottom. The force of gravity and fluid pressure applied above piston 43 cause guide 28 to move to its fully extended position shown in Fig. 2, whereupon lower latch 63 latches the guide in projected position. By reason of the offset or deflected cylindrical section 36, guide 28 locks at an obtuse angle with respect to barrel 26. By rotating drill pipe 23 the tool is turned so that guide 28 projects in the desired direction for new hole 22. The means whereby the guide is accurately located in proper direction forms no part of the instant invention and hence is not herein described, being well understood in this art.

In Fig. 2 the tool is shown in position at commencement of the deflected drilling operation with the guide bit 42 forced firmly into the formation at the bottom of pre-existing hole 21 and offset to one side from the central axis of the pre-existing hole. Lower latch 77 is then unlatched by means heretofore explained and thereupon drill pipe 23 and barrel 26 are lowered and turned, causing core bit 27 to be deflected in the direction of the new bore hole. During deflected drilling, as shown in Fig. 3, fluid pressure is applied above piston 43, thereby holding guide 28 in position. The bending of barrel 26 to accommodate deflection is exaggerated in Fig. 3. The deflected drilling operation is continued until guide 28 is reseated inside barrel 26 and latched

therein, whereupon the tool continues to drill new hole 22 in the proper direction.

The fluid pressure employed against piston 43 may be drilling compound. It is desirable that means for circulation of drilling compound to guide bit 42 be provided while the tool is in drilling position, but not necessarily when the tool is in deflecting position. Accordingly, as shown in Figs. 1-3, inclusive, circulation ports 71 are formed in core bit 27 extending from the deflected cylindrical section 36 to adjacent the bottom of the tool. Similarly, circulation ports 72 are formed in guide bit 42. The location of the entrance of circulation ports 72 is such that when guide 28 is retracted, as shown in Fig. 1, the fluid circulates both through ports 72 in the guide bit and core bit 27. However, as soon as guide 28 is projected, flow through guide bit circulation ports 72 is cut off. Piston 43 is formed with longitudinal circulation ports 73 of restricted size, causing a loss of pressure due to increased friction and the loss of pressure results in a pressure differential above and below piston 43. This pressure differential creates downward thrust on the guide stem, which tends to hold said guide stem in position while deflecting.

A modified latch 77a which holds the guide 28a in retracted position is shown in Fig. 5, wherein the pivot pin 78 on which latch 77a is mounted is located below the working portion 79 of the latch and the latch cavity 34a in the restricted diameter upper portion 32a of barrel 23a is constructed essentially similarly to the corresponding parts shown in Figs. 1-3.

In Fig. 6 the latch 81 which holds the guide 28b in retracted position in barrel 32b is shown further modified, with the pivot pin 82 for the latch located at the top and spring 49b biasing latch 81 outwardly.

The latches of Figs. 5 and 6 may be located either at the upper or lower end of the stems 28a or 28b, or at an intermediate position.

In Fig. 7 is shown a further modification for releasing the latch 86 which holds the guide 28c in deflecting position. In this modification, latch 86 is pivoted by means of pin 87 and biased outwardly by tension spring 88. The barrel 32c of latch cavity 89 is provided with a central cylinder 91 in which reciprocates a double-ended piston 92. Spring 93 in the bottom of cylinder 91 biases the double-ended piston upwardly. The upper end 94 of piston 92 fits within the cylinder 91 and when excessive fluid pressure is applied from the surface, piston 92 is forced down. On the downward stroke, the lower end 96 of piston 92 engages the inner end of latch 86, causing the latch to retract. Upon release of fluid pressure at the surface, spring 93 returns piston 92 to upper position, whereupon latch spring 88 biases latch 86 to extended position. Port 97 in cylinder 91 permits restricted circulation of fluid. It should be noted that, by changing the shape of the latch and position of its pivot, a number of variations may be obtained, any of which will satisfy the need of a latch, lockable or unlockable by use of fluid pressure.

In Fig. 7A is shown a latch similar to that of Fig. 7 modified in that it is employed as an upper latch. Accordingly latch 86a and cavity 89a are shaped for such function and the other parts are substantially the same and are illustrated with the same reference numerals. Spring 88 is of sufficient strength to support the weight of guide 28c when in retracted position.

In the event that it is desired to relatch guide 28 if it should accidentally drop out of barrel 26, a spearhead 101 may be formed above head 44. A conventional overshot (not shown) is lowered into drill pipe 22 on a wire line and is used to engage spearhead 101 to lift 70

After raising guide 28 the tool is lowered to the bottom of the hole and rotated in the direction used for drilling until latch 47 is latched in cavity 34. Then the overshot is released and removed and drilling may be started.

Reference is now made to Figs. 1 and 4 wherein there is provided a latch 77 mounted by means of pivot pin 78 in an appropriate recess in stem 41 and biased outwardly by means of a spring (not shown). Latch 77 extends upwardly outwardly and the upper end 102 thereof is beveled relative to the axis of the tool in a downwardly outwardly direction. Latch cavity 38 formed in core bit 27 is provided with an upper shoulder 103 having a taper complementary to the beveled end 102 of latch 77 and has a side 104 substantially parallel to latch 77 in its extended position. It will be noted with reference to Fig. 1 that the internal diameter of core bit 27 above latch cavity 38 is greater than the corresponding diameter below the latch cavity. The force required to lower or project guide assembly 28 is substantially less than the force required to lower core bit 27 over guide 28. Further, the parts may be constructed so that guide 28 must be pumped into extended position by application of fluid pressure on piston 43, whereas it is desirable that considerable force be required in order to lower core bit 27 over guide 28.

Referring now to Figs. 8 and 8A, there is provided a latch 260 which may be employed for latching the guide 28d both in extended and retracted positions. Latch 260 is pivoted by means of pin 261a in a recess 262a in such manner that it can be moved to an extended position substantially transverse to the axis of rotation of the tool and may be retracted by pivoting upwardly. Spring 264a biases latch 260 outwardly. A pair of latch cavities 266 and 267 are located in the barrel 268. Lower cavity 266 is located so that when guide 28d is in fully projected position, latch 260 is directly opposite the latch cavity 266. Irregularly shaped upper latch cavity 267 formed in the wall of barrel 268 is located in such position that it is directly opposite latch 260 when the guide is in fully retracted position. The lower edge 271 of latch 260 is slanted and the lower edge 272 of cavity 267 is likewise slanted to hold guide 28d in retracted position. The upper edge 276 of latch 260 is bevelled and the upper wall 277 of cavity 267 is likewise bevelled. Upward pressure on guide 28d when sufficient to overcome the force of spring 264 unlatches latch 260. Similarly the upper edge 278 of cavity 266 is slanted to unlatch the latch when upward pressure is applied to guide 28d and this effect is augmented by ball 279 inserted in edge 278.

In the modification shown in Figs. 13-17 the tool is installed on the lower end of a drill stem 220 and lowered into the bottom of pre-existing bore hole 221. The lowermost portion of the tool is a conventional core bit 222, or similar device, the details of the construction of which form no part of this invention. Such a core bit 222 is formed with a central downwardly tapering bore 223 through which, in conventional usage, the core of the hole formation is received. It will be understood that the shape of bore 223 is subject to considerable modification in common commercial practice. Immediately above core bit 222 is a barrel 224 of lesser outside diameter than bit 220. Barrel 224 and core bit 222 are secured together by a threaded connection 226. The barrel 224 is hollow and elongated bore 227 thereof is formed with an offset, outwardly slanted portion 228 adjacent its lower extremity of substantially the same diameter as bore 227. It will be understood that the parts illustrated are round, but often other cross-sectional shapes may be employed. The offset portion 228 slants outwardly in one direction toward the wall of barrel 224 so that hole 228 is offset from the center of barrel 224. Immediately above the lower end of offset hole portion 228 is a shoulder 229 which is located, preferably, on the side of hole 228 toward which the offset portion is offset. Instead of an abrupt shoulder 229, a tapered reduction in hole size may be substituted.

Retractable within bore 227 of barrel 24 is a guide 231 formed of a somewhat flexible rod or tube and

having a diameter substantially equal to the smallest diameter of bore 223 in the core bit or similar device. The lower end of guide 231 is connected to a guide bit 232 which is designed to lodge in the bottom of hole 221. The upper end of guide 231 is formed with an enlarged head 233a, the diameter of which is substantially equal to the diameter of bore 227. Head 233a comprises a piston reciprocable in a cylinder comprising bore sections 227 and 228. Latch 256 which engages in latch cavity 252 holds guide 231 in retracted position.

In use, hole 221 is dug by a conventional bit or by core bit 222 to the required depth, latch 256 maintaining guide 231 retracted (see Fig. 13). If a conventional bit has been employed in drilling hole 221, it is withdrawn and a core bit 222 and barrel 224 installed. In any event, the core bit is raised from the bottom of hole 221 a distance substantially equal to the length of guide 231 and barrel 224 accurately located with shoulder 229 offset in the proper direction so that guide 231 will be projected parallel to the direction of the slant hole to be drilled (Fig. 14).

It will be understood that in conventional drilling practice drilling mud is pumped through the hollow stem into the bottom of the drill hole. This feature of conventional drilling apparatus is used in the present invention. The mud or some other suitable fluid is pumped through hollow drill stem 220 into hole 227 in barrel 224. The pressure of the fluid on guide head 233a forces the guide head downwardly until guide 231 projects through bore 223. Thereupon additional weight is applied and guide bit 232 lodges securely in the bottom of hole 221 (Fig. 14). With guide bit 232 lodged in the position shown in Fig. 14, drill stem 220 is lowered. Accordingly, flexible drill guide 231 is bent slightly, allowing core bit 222 to go down hole 221 far enough so guide head 233a is removed from offset portion 228 and positioned in bore 227 (see Fig. 15). The drill is then rotated. By reason of the fact that guide 231 is offset, pressure is exerted against the side of hole 221 and slant drilling commences. Drill stem 220 is lowered and turned slowly, resulting in divergent drilling of slant hole 236 as bit 222 follows guide 231. During the operation, fluid pressure is maintained against head 233a in order that guide bit 232 be maintained in position. When normal drilling of slant hole 236 may be commenced, the hole guide is retracted in barrel 224 (Fig. 16). In normal usage, as shown in Fig. 16, sufficient drilling fluid flows between head 233a and bore 227 for normal circulation. Excessive pressure or volume of fluid causes projection of the stem. This same relationship exists for Figs. 19 and 20.

As shown in Fig. 18, guide 231 may be relieved in a neck 241 so that the diameter of rod 231 is reduced. This eliminates the necessity of guide 231 bending, as set forth in the preceding paragraph, during the commencement of slant drilling. The length of the reduced diameter portion 241 should be substantially the same as the length of offset section 228. Latch 256 is similar to that described in Figs. 19-21 hereinafter described.

Turning now to the illustration shown in Figs. 19, 20 and 11, inclusive, it is desirable to latch guide 231 inside barrel 224 during certain portions of the cycle of operation. Various means may be employed to latch guide head 233, guide 231 or bit 232 in such retracted position. As shown in Figs. 19, 20 and 11, barrel 224 is formed with a reduced diameter shoulder 251 which forms a limit for the upward movement of head 233. Spaced downwardly from the shoulder in the interior wall of barrel 224 is latch cavity 252, the upper wall 253 of said latch cavity being downwardly, outwardly diverging and the lower wall 254 of cavity 252 likewise being downwardly, outwardly diverging. Latch 256 carried by head 233 fits into latch cavity 252, and as shown in Fig. 19, when in latched position limits downward movement of head 233 relative to barrel 224.

Head 233 is formed with a peculiarly shaped recess 257 extending downwardly from the top of the head. An abutment 258 is formed in head 233 which limits upward movement of latch 256. Latch 256 is mounted in recess 257 on horizontal pivot pin 259 and moves from latched position in full lines in Fig. 20 to the unlatched position shown in dotted lines in Fig. 20. Extension 261 of recess 257 provides clearance for latch 256 when the latter is in unlatched position. Spring 262 at the bottom of hole 257 biases the inner end or head 263 of latch 256 upwardly and thus biases latch 256 into unlatched position. Head 263 is substantially circular, as shown in Fig. 11, and fits tightly against a portion 264 of the hole, which functions as a cylinder, whereas head 263 functions as a piston. As fluid pressure is applied through drill stem 220, barrel 224 is rotated until its position relative to latch 256 is that shown in solid lines in Fig. 20. When barrel 224 is then raised, a combination of gravity and pump pressure, or either alone, hold head 263 and latch 256 in the position as shown in Fig. 19. The force of spring 262 is such that it will raise head 263, thus unlatching latch 256, when fluid pressure is released, and guide bit 232 put on bottom to force head 233 to uppermost position, since neither gravity nor pressure are acting on head 263 or latch 256 in this position.

The foregoing construction permits the tool to be run in the hole in retracted position with the weight of head 233, guide 231 and bit 232 maintaining the latch in locked position, as shown in Fig. 19. During conventional drilling, the fluid pressure against head 263 maintains latch 256 in locked position, as shown in solid lines in Fig. 20. When it is desired to commence slant drilling, rotation of bit 222 is stopped and fluid pressure released while bit 222 is still on the bottom of hole 221. Thereupon spring 262 raises head 263 unlocking latch 256 in the position shown in dotted lines in Fig. 20. The barrel is then raised, the weight of head 233, guide 231 and bit 232 causing themselves to slide through barrel 224 into the extended position as shown in Fig. 19.

In the modification of the invention shown in Fig. 10, the guide 121 comprises a stem 122 having a bit 123 on its lower end and an enlargement 124 intermediate the ends which cooperates with a seat 126 in the core bit 127 to act as a fulcrum to deflect the guide. Above ball 124 is a knuckle joint 128 to which the upper or piston part 129 of the guide is attached. Piston 129 tapers inwardly from top to bottom. Knuckle joint 128 is provided with a shoe 131 attached to piston 129 carrying helical coil spring 132, the outer end of which carries a second shoe 133 sliding on the inner wall of the barrel 134. The pressure of spring 132 against knuckle joint 128 biases guide to deflected position. Accordingly, as guide 121 is lowered inside the barrel, it is deflected the maximum deflection being as indicated in Fig. 10. Upper and lower latches 136 and 137, respectively, serve to latch the guide in retracted and projected positions as in the preceding modifications. As a further modification the spring may be secured to the barrel rather than to the guide.

In the modification shown in Fig. 9, a flexible stem 171 is provided. For this purpose the middle portion of the stem is made in two sections, 172 and 173, with a knuckle joint 174 between the two sections. Knuckle joint 174 is spring-loaded by means of helical spring 176 to require the lower section 173 of the stem to assume an angle relative to upper section 172, which angle determines the degree of deflection of the hole. However, the force of spring 176 in the knuckle joint is such that when the tool is retracted, the upper and lower sections 172 and 173 assume a lesser angle which facilitates retraction of the guide within the barrel.

The modification of Fig. 12 is employed to straighten a hole into vertical alignment when it has diverged from vertical direction. Accordingly, the stem 161 of guide

162 is formed in two sections 161a and 161b with a knuckle joint 163 between the two sections. When in projected position the lower section 161b by reason of the attraction of gravity, assumes a vertical direction. The reference numerals of other parts correspond with those in Fig. 1.

Although the foregoing invention has been described in some detail by way of illustration and example for purposes of clarity of understanding, it is understood that certain changes and modifications may be practiced within the spirit of the invention and scope of the appended claims.

I claim:

1. In combination, a barrel, a centrally apertured bit on the lower end of said barrel, a guide extensible and retractable in said barrel through the central aperture of said bit, a guide bit on the lower end of said guide, latching and unlatching means operable to latch said guide alternately and repeatedly in extended and in retracted positions and to unlatch said guide, and means operable from a position remote from said barrel for actuating said latching and unlatching means, said last-mentioned means including a drill stem.

2. The combination according to claim 1 wherein said unlatching means comprises upper latch means located in said barrel and guide to hold said guide in retracted position with said centrally apertured bit and guide bit in juxtaposition for drilling and in which said latching means further comprises lower latch means located in said barrel and guide to hold said guide in extended position said centrally apertured bit for drilling around said guide as a center while said guide remains substantially stationary in a vertical sense.

3. The combination according to claim 2 wherein said latching means are located in said barrel so that said centrally apertured bit drills down over said guide until said centrally apertured bit is in juxtaposition with said guide bit and said latching means latches said guide in retracted position.

4. In combination, a core bit having a substantially central aperture, a barrel above said bit, said barrel being formed with a bore diverging outwardly toward the side wall of said barrel adjacent the lower end thereof, and a guide within said barrel having a stem dimensioned to project outwardly through said aperture in said bit, said stem slideable within said bore in said barrel and tiltable about said aperture as a fulcrum as the inner end of said stem diverges outwardly in said barrel, a guide bit on the lower end of said stem, and cooperating means on said guide and said barrel to latch said guide with said guide bit substantially retracted within said first mentioned bit, said cooperating means being repeatedly movable between latched and unlatched positions.

5. The combination of claim 4 which further comprises second cooperating means on said guide and said barrel to latch said guide bit with said guide bit extended remote from said barrel and with said guide bit offset laterally relative to the longitudinal central axis of said barrel.

6. The combination of claim 4 in which said barrel is formed with an internal abutment adjacent the lower end of said bore adapted to engage said guide to limit outward movement of said guide.

7. In combination, a core bit having a substantially central aperture, a barrel above said bit adjacent the lower end of said aperture, said barrel being formed with a bore diverging outwardly toward the side wall of said barrel adjacent the lower end thereof, a guide within said barrel having a guide bit, and a stem dimensioned to project outwardly through said aperture in said bit, said stem being tiltable about said aperture as a fulcrum as the inner end of said stem diverges outwardly in said barrel, cooperating latch means on said barrel and on said guide, said latch means being cooperable to engage in latching relationship when engaged holding said guide

in elevated position within said barrel, and unlatching means operable to move said latch means to unlatched position responsive to drilling fluid pressure within said barrel above said head.

5 8. In combination, a core bit having a substantially central aperture, a barrel above said bit, said barrel being formed with a bore diverging outwardly toward the side wall of said barrel adjacent the lower end thereof, a guide within said barrel having a stem dimensioned to project outwardly through said aperture in said bit slideable within said bore in said barrel, a head on said stem, and a guide bit on the lower end of said stem, said guide bit diverging outwardly in a direction opposite the direction of divergence of said bore as said stem tilts about said aperture as a fulcrum, said barrel being formed with a latch hole therein, said head being hollow, a latch in said head and projecting outwardly to engage said latch-hole in said barrel when said latch is in latched position, means biasing said latch toward latched position, and means responsive to drilling fluid pressure within said barrel above said head to move said latch to unlatched position.

9. In combination, a bit having a substantially central aperture, a barrel above said bit, and a guide within said barrel having a stem dimensioned to project outwardly through said central aperture, a head on the upper end of said stem slideable within said barrel, and a guide bit on the lower end of said stem, said stem being provided with a knuckle joint intermediate its length, resilient means biasing the portion of said stem below said knuckle joint disposed at an angle relative to the portion of said stem above said knuckle joint, and latching and unlatching means operable to latch said stem alternately and repeatedly in extended and in retracted positions and to unlatch said stem, and means operable from a position remote from said barrel for actuating said latching and unlatching means.

10. The combination according to claim 9 wherein said knuckle joint is located exteriorly of said barrel when said stem is in projected position.

11. The combination according to claim 9 wherein said knuckle joint is located interiorly of said barrel when said stem is in projected position.

12. In combination, a barrel, said barrel being provided with a bit at its lower end, said bit having an aperture, a guide extensible and retractable within said barrel having a stem dimensioned to project outwardly through said central aperture, a head on the upper end of said stem slideable within said barrel with a close fit, a guide bit on the lower end of said stem, said stem having an upper portion and a lower portion disposed at an angle relative to said upper portion, said barrel and head being provided with cooperating means to locate the portion of said stem below the angle positively disposed relative to said barrel when said guide is projected, and latching and unlatching means operable to latch said stem alternately and repeatedly in extended and in retracted positions and to unlatch said stem, and means operable from a position remote from said barrel for actuating said latching and unlatching means.

13. In combination, a barrel, a bit on the lower end of said barrel having a substantially central aperture, a guide disposed partially within said barrel and extensible through said central aperture in said bit, said guide being dimensioned to project outwardly through said central aperture, and a guide bit on the lower end of said guide, said guide and said barrel having cooperating means whereby, upon extension of said guide, said guide bit is disposed offset relative to the central axis of said barrel, said guide being dimensioned to permit retraction of said guide bit substantially completely within said barrel, said guide being of slightly lesser size than the inside of said barrel and slideable within said barrel for repeated projections and retractions of said guide bit without withdrawal of said barrel, bit or guide from the hole being

drilled, first cooperative latching means on said guide and barrel movable repeatedly between latched and unlatched positions, said first cooperative latching means when in latched position holding said guide retracted in said barrel, and second cooperative latching means on said guide and barrel movable repeatedly between latched and unlatched positions, said second cooperative latching means when in latched position holding said guide in projected position, said guide being retained in either projected or retracted position against unintentional dislodgment from projected or retracted position.

14. The combination of claim 13 which further comprises means operable from a position remote from said barrel for unlatching said first cooperative latching means, said last-mentioned means including a drill stem.

15. A directional drilling device comprising a drill bit, said drill bit being formed with a central bore, a hollow barrel secured above said drill bit, a guide movable within said barrel and extendable through said bore, means to restrain complete withdrawal of said guide from said barrel, said guide comprising a stem, and a guide bit on the lower end of said stem, said stem having an upper portion and a lower portion disposed at an angle relative to said upper portion whereby, upon projection of said guide, said guide bit extends at an angle relative to the direction of said drill bit, said guide fitting against the inner wall of said barrel, whereby upon application of fluid pressure from the top of said barrel, said guide is projected, first cooperative latching means on said guide and barrel movable repeatedly between latched and unlatched positions, said first cooperative latching means when in latched position holding said guide retracted in

5 said barrel, and second cooperative latching means on said guide and barrel movable repeatedly between latched and unlatched positions, said second cooperative latching means when in latched position holding said guide in projected position, said guide being retained in either projected or retracted position against unintentional dislodgment from projected or retracted position.

16. The combination of claim 14 in which said last named means is responsive to fluid pressure in said barrel.

17. The combination of claim 14 in which said last named means is responsive to mechanical movement of said barrel.

18. A device according to claim 15 in which said means to restrain complete withdrawal comprises a shoulder 15 formed in said bit and an enlarged portion adjacent the upper end of said shank of said guide.

19. A device according to claim 15 in which the upper 20 end of said bore is counterbored to provide a shoulder in said bit and in which said means to restrain complete withdrawal comprises an enlargement on said stem dimensioned to fit within the counterbored portion of said bore and seat on said shoulder.
